UNITED STATES PATENT OFFICE.

CHARLES E. GROSBERG, OF OAKLAND, CALIFORNIA.

SUPPORTER.

Application filed April 18, 1922. Serial No. 555,093.

To all whom it may concern:

Be it known that I, CHARLES E. GROSBERG, a citizen of Russia, residing at Oakland, in the county of Alameda and State of California, have invented certain new and useful Improvements in Supporters, of which the following is a specification.

My invention is a holder which may be connected to the front and back of a corset worn by women or an abdominal belt worn by men and extends between the legs of the wearer for holding the corset or belt down in place, for holding up the flesh of the buttocks of corpulent persons, for holding a sanitary napkin for women when connected to a corset, and for supporting the testicles of men when connected to an abdominal belt.

Referring to the annexed drawing in which my invention is illustrated and which forms a part of this specification:

Figure 1 is a perspective view of my holder and a corset to which my holder is connected.

Figure 2 is a perspective view of my holder and an abdominal belt to which my holder is connected.

My holder comprises a fabric apron 1, wide at one end and narrow at the other end, a fabric strap 2 and three elastic bands 3 arranged side by side and connected at one end to the narrow end of said apron and at their other ends to one end of said strap. The wide end of said apron is detachably connected to the lower edge of a corset or abdominal belt 5 at the rear and part way forwardly thereof, by hooks and eyes 6 so that the wide upper part of said apron extends forwardly about half way around the hips of the wearer, whereby the flesh of the buttocks of corpulent persons may be held up. The forward end of the strap 2 is detachably fastened to the lower part of the front of the corset or belt by snap buttons 7, which comprise three socket members 8 secured on the forward end of said strap and nine stud members 9 secured on the front of the corset or belt in three superimposed rows with three of said members in each row, over the stud members of which rows respectively said socket members are adapted to snap, whereby the strap may be adjustably connected at different effective lengths to fit the wearer properly. My holder when connected to a corset and worn by a woman will effectively hold a sanitary napkin. When connected to an abdominal belt and worn by a man the strap 2 may be formed with an outward bulge 10 to receive and support the man's testicles.

Having described my invention, I claim:

1. A holder comprising an apron, a strap, elastic bands connecting said apron and said strap, means for connecting said apron to the lower edge of a corset or abdominal belt at the rear and part way forward at the sides of said corset or belt, and means for connecting the forward end of said strap to the front of the corset or belt. 70

2. A holder comprising an apron, a strap, elastic bands connecting said apron and said strap, means for connecting said apron to the lower edge of a corset or abdominal belt at the rear and part way forward at the sides of said corset or belt, and means for connecting the forward end of said strap to the front of the corset or belt at different effective lengths. 75

3. A holder comprising an apron wide at one end and narrow at the other end, a strap, elastic bands connecting said strap and the narrow end of said apron, means for connecting said apron to the lower edge of a corset or abdominal belt at the rear and part way forward at the sides thereof, and means for connecting the forward end of said strap to the front of the corset or belt. 80

4. A holder comprising an apron, a strap, elastic bands connecting said apron and said strap, hooks and eyes for connecting said apron to the lower edge of a corset or abdominal belt at the rear and part way forward at the sides thereof, and means for connecting the forward end of said strap to the front of the corset or belt. 90

5. A holder comprising an apron, a strap, elastic bands connecting said apron and said strap, means for connecting said apron to the lower edge of a corset or abdominal belt at the rear and part way forward at the sides of said corset or belt, and snap buttons for connecting the forward end of said strap to the front of the corset or belt. 100

6. A holder comprising an apron, a strap, elastic bands connecting said apron and said strap, means for connecting said apron to the lower edge of a corset or abdominal belt at the rear and part way forward at the sides of said corset or belt, two substantially vertical rows of stud members carried on the front part of the corset, socket mem- 110

bers carried by the strap and adapted to detachably fasten the strap to the stud members whereby the effective length of the strap may be varied.

5 7. A holder comprising an apron, a strap, elastic bands connecting said apron and said strap, means for connecting said apron to the lower edge of a corset or abdominal belt at the rear and part way forward at the 10 sides of said corset or belt, two substantially vertical rows of stud members carried on the front part of the corset, socket members carried by the strap and adapted to detachably fasten the strap to the stud members whereby the effective length of the strap may be varied, said strap member being formed with a bulge intermediate its ends.

In testimony whereof I affix my signature.

CHARLES E. GROSBERG.
